Patented Dec. 18, 1928.

Des. 77,272

UNITED STATES PATENT OFFICE.

WESTERN UNDERWOOD, OF LOS ANGELES, CALIFORNIA.

DESIGN FOR A STREET-LIGHTING POST.

Application filed October 4, 1928. Serial No. 28,365. Term of patent 7 years.

To all whom it may concern:

Be it known that I, WESTERN UNDERWOOD, a citizen of the United States, residing at Los Angeles, in the county of Los Angeles and State of California, have invented a new, original, and ornamental Design for a Street-Lighting Post, of which the following is a specification, reference being had to the accompanying drawing, forming a part thereof.

The figure is a side elevation.

I claim:

The ornamental design for a street lighting post, as shown.

WESTERN UNDERWOOD.
